ABSTRACT

A beam to column joint connection structure of a building
framework has a column assembly and a beam assembly.
The column assembly includes a column, a pair of gusset
plates on opposite sides of the column, and bearing ele-
ments. The beam assembly includes a beam having an end
portion received between the gusset plates. The beam as-
sembly has bearing elements. The bearing elements are po-
sitioned with respect to each other to prevent movement of the
beam assembly relative to the column assembly by enga-
gement of exterior bearing engagement surfaces of the bearing
elements of the column assembly with exterior engagement
surfaces of the bearing elements of the beam as-
sembly in a direction along a longitudinal axis of the beam. The
beam-to-column joint connection does not require any bolts
or welds connecting the beam assembly to the column
assembly, resulting in an all bearing moment connection.

GUSSET PLATE CONNECTION IN BEARING
OF BEAM TO COLUMNCROSS-REFERENCE TO RELATED
APPLICATIONS

This application is a continuation-in-part of U.S. patent application Ser. No. 14/233,953, filed Jan. 21, 2014 and titled GUSSET PLATE CONNECTION OF BEAM TO COLUMN, which is the U.S. national phase entry of PCT application No. PCT/US2013/072368, filed Nov. 27, 2013. This application and the '953 application also claim the benefit of priority under 35 U.S.C. §119 to U.S. Patent Application No. 61/732,015, titled GUSSET PLATE CONNECTION OF BEAM TO COLUMN, which was filed on Nov. 30, 2012, and U.S. Patent Application No. 61/798,041, titled GUSSET PLATE CONNECTION OF BEAM TO COLUMN, which was filed on Mar. 15, 2013 and which are incorporated herein by reference in their entireties for all purposes.

FIELD OF THE INVENTION

The present invention generally relates to a moment resisting, beam-to-column joint connection structure.

BACKGROUND OF THE INVENTION

It has been found in a moment-resisting building having a structural steel framework, that most of the energy of an earthquake, or other extreme loading condition, is absorbed and dissipated, in or near the beam-to-column joints of the building.

In the structural steel construction of moment-resisting buildings, towers, and similar structures, most commonly in the past, the flanges of beams were welded to the face of columns by full-penetration, single bevel, groove welds. Thus, the joint connection was comprised of highly-restrained welds connecting a beam between successive columns. Vertical loads, that is, the weight of the floors and loads superimposed on the floors, were and still are assumed by many to be carried by vertical shear tabs or pairs of vertical, structural angle irons arranged back-to-back, bolted or welded to the web of the beam and bolted or welded to the face of the column.

The greater part of the vertical load placed upon a beam was commonly assumed to be carried by a shear tab bolted or welded to the web of the beam and bolted or welded to the face of the flange of the column at each end of the beam. Through the use of face-to-face gusset plates welded to the column, the greater part of the vertical load is carried by the gusset plates.

Experience has shown that the practice of welding the beam's flanges directly to the column is uncertain and/or unsuitable for resistance to earthquakes, explosions, tornadoes and other disastrous events. Such connection means and welding practice has resulted in sudden, fractured welds, the pulling of divots from the face of the column flange, cracks in the column flange and column web, and various other failures. Such highly-restrained welds do not provide a reliable mechanism for dissipation of earthquake energy, or other large forces, and can lead to brittle fracture of the weld and the column, particularly the flange of the column and the web of the column in the locality of the beam-to-column joint, (known as the "panel zone").

It is desirable to achieve greater strength, ductility and joint rotational capacity in beam-to-column connections in

2

order to make buildings less vulnerable to disastrous events. Greater connection strength, ductility and joint rotational capacity are particularly desirable in resisting sizeable moments in both the lateral and the vertical plane. That is, the beam-to-column moment-resisting connections in a steel frame building can be subjected to large rotational demands in the vertical plane due to interstory lateral building drift. Engineering analysis, design and full-scale specimen testing have determined that prior steel frame connection techniques can be substantially improved by strengthening the beam-to-column connection in a way which better resists and withstands the sizeable beam-to-column, joint rotations which are placed upon the beam and the column. That is, the beam-to-column connection must be a strong and ductile, moment-resisting connection.

Reference is made to co-assigned U.S. Pat. Nos. 5,660,017, 6,138,427, 6,516,583, and 8,205,408 (Houghton et al.) for further discussion of prior practice and the improvement of the structural connection between beams and columns through the use of gusset plates. These patents illustrate the improvements that have been manifested commercially in the construction industry by Houghton and others in side plate technology. Initially, side plate construction was introduced to greatly improve the quality of the beam-to-column connection. Further improvements included the provision of side plate technology using full length beams to achieve greater economy and to facilitate more conventional erection techniques.

SUMMARY

In one aspect, a joint connection structure of a building framework generally comprises a column assembly including a column having a longitudinal axis and a pair of gusset plates connected to the column on opposite sides of the column and extending laterally outward from the column. The bearing elements are operatively connected to the gusset plate and project from the gusset plate. The bearing elements each have an exterior bearing engagement surface. A beam assembly includes a beam having a longitudinal axis, upper and lower flanges, an end portion received between the gusset plates, and at least one bearing element operatively connected to the beam and projecting from the beam. The bearing element has an exterior bearing engagement surface. The bearing elements of the column assembly and the bearing element of the beam assembly are positioned with respect to each other for engagement of the exterior bearing engagement surfaces of the bearing element of the column assembly with the exterior engagement bearing surfaces of the bearing element of the beam assembly to prevent movement of the beam assembly relative to the column assembly in a direction along the longitudinal axis of the beam.

In another aspect, a prefabricated column assembly is constructed for mounting a beam assembly on the column assembly. The column assembly generally comprises a column and a pair of gusset plates connected to the column on opposite sides of the column and extending laterally outward from the column. The gusset plates are configured for receiving a beam of the beam assembly therebetween to connect the beam assembly to the column. A plurality of bearing elements are attached to at least one of the gusset plates in spaced apart arrangement for receiving and interlocking with at least one corresponding bearing element on the beam assembly therebetween for moment connecting the beam assembly to the column assembly.

In yet another aspect, a prefabricated beam assembly is constructed for mounting connection to a column assembly.

The beam assembly generally comprises a beam and a plurality of bearing elements operatively attached to the beam in spaced apart arrangement for receiving and interlocking with a plurality of corresponding bearing elements on the column assembly therebetween for moment connecting the beam assembly to the column assembly.

Other objects and features of the invention will in part be apparent and in part pointed out hereinafter.

BRIEF DESCRIPTION OF THE DRAWINGS

FIG. 1 is a fragmentary perspective of a beam-to-column joint connection structure of a first embodiment;

DESCRIPTION OF THE PREFERRED EMBODIMENTS

Referring to FIGS. 1-12, a beam-to-column moment-resisting joint connection structure of a first embodiment is generally indicated at 11. The joint connection structure may be used in the construction of a building framework F (see FIG. 1A). In the illustrated embodiment, the joint connection joins a column assembly 13 including a column 15 to a full-length beam assembly 17 including a full-length beam 19. A full-length beam is a beam that has a length sufficient to extend substantially the full-length between adjacent columns in a structure. Thus, a stub and link beam assembly as shown in FIGS. 5 and 16 of U.S. Pat. No. 6,138,427, herein incorporated by reference, is not a full-length beam. It is understood that the joint connection structure may be a beam-to-column type as shown, or a beam-to-column-to-beam type as shown in U.S. Pat. No. 8,146,322, herein incorporated by reference, depending upon the location of the joint connection structure within a building's framework.

The beam 19 and column 15 may have any suitable configuration, such as an I-beam, H-beam configuration, or hollow rectangular shape (built up box member or HSS tube section). A spaced apart pair of parallel, vertically and horizontally extending gusset plates 21 sandwich the column 15 and beam 19. Four optional horizontal shear plates 23 (only three are shown in FIG. 1) are arranged in vertically spaced pairs generally aligned at top and bottom edges of the gusset plates 21. A horizontal cover plate 27 is disposed on top of an end of the beam 19. The cover plate 27 is attached in a suitable manner such as by weld 29 to the upper flange of the beam 19. The cover plate 27 may have a width that is greater than a width of the beam 19 and a horizontal spacing of the gusset plates 21. The configuration of the cover plate 27 allows the beam 19 to be lowered between the gusset plates 21 so that one end of the full-length beam assembly 17 is initially supported in bearing between the cover plate 27 and the top edge of the horizontal extension of the gusset plates 21 of the column assembly 13. In other words, the beam 19 is self-shoring. Preferably, the cover plate 27 may rest on a top face of a projecting horizontal leg of upper

angle irons 31 which will be explained in greater detail below. The cover plate 27 extends along the length of the beam 19 and terminates generally at the ends of the gusset plates 21. The cover plate 27 has an oblong radiused slot opening 30 extending along the length of the cover plate. It will be understood that the cover plate 27 may have other widths, configurations and slot-type oblong openings. For example, a cover plate (not shown) may extend beyond the ends of the gusset plates 21 and/or have no slot opening 30.

Referring to FIGS. 1-8, each gusset plate 21 has an upper angle iron 31 (broadly, "an upper connecting member") attached to an outer surface of the gusset plate. The upper angle iron 31 comprises an elongate L-shaped member including a vertical first leg attached to the outer surface of the gusset plate 21 at an upper portion of the gusset plate and extending horizontally along the upper portion of the gusset plate. The first leg of each upper angle iron 31 is attached in a suitable manner such as by weld 29 to the outer surface of the respective gusset plate 21. (FIG. 4). A horizontal second leg of the upper angle iron 31 projects from the vertical first leg of the upper angle iron and laterally away from the gusset plate 21 and away from the beam 19. The second leg of each upper angle iron 31 is attached in a suitable manner such as by weld 29 to a top edge of the gusset plate 21. In the illustrated embodiment, the first and second legs of the upper angle irons 31 are disposed at substantially a right angle to each other. A top surface of the horizontal second leg of each upper angle iron 31 is bolted to a bottom surface of the cover plate 27 by horizontally spaced bolts 26 extending through aligned bolt holes 26A in the second leg of the upper angle irons and cover plate. In another embodiment (not shown), the upper angle irons 31 can be configured such that the lateral edges of the second legs project laterally past the lateral edges of the cover plate 27 to provide a ledger support for metal floor decking spanning perpendicular to beam 19. This reduces construction cost by reducing steel material and welding time, and by speeding the floor construction of the building. Similarly, the horizontal shear plates 23 can extend laterally (perpendicular to the column web) to also serve as metal decking support if there is no perpendicular steel frame member framing into the gusset plates 21. Further, the top surfaces of the second legs of the upper angle irons 31 are disposed above the top edges of the gusset plates 21 to allow welds between the top edges of the gusset plates 21 and the interior faces of the vertical first legs of the angle irons 31. The upper angle irons 31 may be otherwise configured and/or arranged within the scope of the present disclosure.

Referring to FIGS. 4 and 9-12, lower angle irons 33 (broadly, "lower connecting members") are attached to a bottom surface of the bottom flange of the full-length beam 19. The lower angle irons 33 may comprise elongate L-shaped members including a horizontal first leg attached to the bottom surface of the bottom flange of the beam 19 at opposite side portions of the beam and extending horizontally along the side portions. The first leg of each lower angle iron 33 is attached in a suitable manner such as by weld 29 to the bottom surface of the bottom flange of the beam 19, and along the bottom flange tips of the beam 19. Each lower angle iron 33 may also include a second leg projecting from the first leg of the lower angle iron and downward, away from the beam 19. In the illustrated embodiment, the first and second legs of each lower angle iron 33 are disposed at substantially a right angle to each other. An outer surface of the vertical second leg of each lower angle iron 33 is bolted to an inner surface of a respective gusset plate 21 by horizontally spaced bolts 26 extending through aligned bolt

11

holes 26A in the second leg of the lower angle iron and the gusset plate 21. In the illustrated embodiment, the lower angle irons 33 are configured such that the horizontal first legs extend laterally past the lateral edges of the bottom flange of the beam 19 so the outer surfaces of the vertical second legs are disposed laterally away from the flange tips of the bottom flange of the beam 19. The lower angle irons 33 may be otherwise configured and/or arranged within the scope of the present invention. Although angle irons 33 are illustrated, other forms of connecting members may be used.

The joint connection structure 11 outlined above is a beam-to-column type structure. It will be understood by a person having ordinary skill in the art that a beam-to-column-to-beam type structure will have additional analogous components. Most preferably, each of the components of the joint connection structure 11, as well as the beam 19 and column 15, are made of structural steel. Some of the components of the joint connection structure 11 are united by welding and some by bolting. The welding may be initially performed at a fabrication shop. The bolting may be performed at the construction site, which is the preferred option in many regions of the world.

Referring to FIG. 9, the full-length beam assembly 17 may be fabricated at a fabrication shop prior to being transported to the construction site. To fabricate the full-length beam assembly 17, the cover plate 27 is welded at 29 or otherwise attached to the upper flange of the beam. Welding (such as by weld 29) is carried out between the periphery of the slot opening 30 and the top flange of the beam 19, and along the top flange tips of the beam on the underside of the cover plate. The slot opening 30 provides additional flexibility for field installation for cases where there is a skewed orientation of the top beam flange (non-plumb slant) relative to the plumb web of the beam 19, where the erector needs to rotate the beam slightly around its longitudinal axis to resolve a particular beam-to-column erection fit up concern, or where there is a lateral horizontal offset in the beam or column 15 (in the out-of-plane direction, perpendicular to the plane of the moment-resisting frame). The slot opening 30 also reduces out of plane bowing during the welding processes, thus improving performance. The slot opening 30 also allows for smaller sized fillet welds connecting the cover plate 27 to the top surface of the upper flange and to the upper flange tips of the beam 19. This permits the cover plate 27 to be connected to the upper flange of the beam 19 using only one pass welds, which reduces construction time and material cost. The lower angle irons 33 are welded at 29 or otherwise attached to the bottom flange of the beam and project laterally outwardly from the beam. Any welds needed to form the full-length beam assembly 17 can be carried out at the shop. In a preferred embodiment, the welds 29 are fillet welds. Fillet welds do not require ultra-sonic inspection which results in reduced shop fabrication costs. However, the welds could be groove welds or stitch welds. Other welds are also within the scope of the present disclosure. The cover plate 27 and lower angle irons 33 may have other configurations than those illustrated in the current embodiment.

Referring to FIG. 5, the column assembly 13 may also be fabricated at a fabrication shop and later transported to the construction site. To fabricate the column assembly 13, the gusset plates 21 are welded at 29 or otherwise attached to the flanges of the column 15, the optional horizontal shear plates 23 are welded at 29 or otherwise attached to the web of the column and to the top and bottom edges of the gusset plates, and the upper angle irons 31 are welded at 29 or otherwise attached to the gusset plates 21. Thus, at the shop, the

12

column assembly 13 can be constructed exclusively by welds. In a preferred embodiment, the welds 29 are fillet welds. Fillet welds do not require ultra-sonic inspection which results in reduced shop fabrication costs. However, the welds could be groove welds or stitch welds. Other welds are also within the scope of the present disclosure. The horizontal shear plates 23 can be omitted from the column assembly 13 and the gusset plates 21 may have other configurations than shown.

At the construction site, the column assembly 13 is joined to the full-length beam assembly 17. The column assembly 13 is first erected in a vertical orientation and the end of the full-length beam assembly 17 is positioned horizontally and adjacent to the column assembly, so that each end of the beam is over a respective pair of gusset plates 21. The full-length beam assembly 17 is then lowered between the gusset plates 21 until the bottom surface of the cover plate 27 engages the top surfaces of the horizontal second legs of the upper angle irons 31. This engagement initially locates and supports the full-length beam assembly 17 on the column assembly 13 to facilitate shoring during erection. To fixedly secure the two assemblies 13, 17 bolts 26 are used to attach the upper angle irons 31 to the cover plate 27 and the lower angle irons 33 to the gusset plates 21 through aligned bolt holes 26A in the respective components. Bolt holes 26A in the cover plate 27 are slotted perpendicular to the longitudinal axis of the beam 19 (e.g., elongated as shown in FIG. 11) to facilitate attachment and erection fit up of the cover plate to the upper angle irons 31. In addition to or instead of the slotting of the bolt holes 26A in the cover plate 27, corresponding bolt holes in the horizontal second leg of each upper angle iron 31 can be slotted perpendicular to the longitudinal axis of the beam. Bolt holes 26A near the bottom edge of the horizontal extension of gusset plates 21 may also be slotted in the vertical direction (e.g., elongated as shown in FIG. 6) to facilitate attachment and erection fit up of the lower angle irons 33 to the gusset plates. In addition to or instead of slotting the bolt holes 26A in the gusset plates 21, corresponding bolt holes in the second leg of the lower angle irons 33 can be slotted in the vertical direction. Thus, at the construction site, the beam-to-column moment-resisting joint connection structure 11, which includes a full-length beam assembly 17, is completed exclusively through bolted connections. In the field, the joint connection structure 11 is constructed without the use of welds. The cover plate 27 is designed to transfer most, if not all, of the vertical shear load from the full-length beam 19, thus eliminating the need for the vertical shear plates 23, while also reducing material and construction costs. This full-length beam, all field bolted joint connection structure employing gusset plates was not appreciated in conventional joint connection structures.

The intentional offset positioning of the top horizontal edge of the gusset plates 21 slightly below the top of steel 55 elevation of the beam 19, a result of the top surfaces of the second legs of the upper angle irons 31 being disposed above the top edges of the gusset plates 21, precludes the inadvertent non-plumb positioning of the top edge of the gusset plates from affecting the desired near flush contact between the cover plate 27 and the top faces of the horizontal leg of the upper angle irons 31 prior to bolting these two components together. This is because the top edges of the gusset plates 21 are vertically spaced below the interface between the angle irons 31 and cover plate 27 providing space for the angle irons 31 to be suitably positioned to account for any inadvertent non-plumb positioning of the gusset plates with respect to the column 15. In particular, the vertical leg of

13

each upper angle iron 31 is positioned plumb to the column's web in the shop and welded in that position to the gusset plates 21 regardless of any possible non-plumb positioning of the top horizontal edge of the gusset plates with respect to the column 15, thus achieving a near flush fit up. The offset of the horizontal legs of the angle irons 31 above the upper edges of the gusset plates 21 also allows the vertical leg of the upper angle irons 31 to be horizontally welded to the gusset plates 21 at two locations, the first being at the toe of the vertical leg of the angle iron, and the second being near the heel of that vertical leg, thus improving significantly the performance of load transfer between the gusset plates 21 and their respective connecting upper angle irons 31 by providing a force couple that increases strength of the attachment of the angle iron to the gusset plate.

The geometry of the bolted joint connection structure 11 including the widened cover plate 27 inherently maximizes the efficiency of cost and time of field installation because the design geometry can specifically accommodate worst-case scenarios of cumulative permissible variations in cross section for rolled steel column and beam shapes (referred to in the industry as "standard mill practice tolerances"), resulting in less probability of field adjustments needed to accommodate as-built column assemblies and full-length beam assemblies. In particular, the joint connection structure 11 can account for possible vertical separation (or gap) between the underside of the cover plate 27 and the upper angle irons 31, due to a skewed (non-plumb to the web of the beam 19 but within standard mill practice) upper flange orientation of the beam 19. In particular, the clamping action of the upper bolts 26 upon being tensioned during installation automatically closes the gap between the cover plate 27 and the upper angle irons 31, through deformation of the cover plate and the horizontal legs of the upper angle irons. In this way, the need for burdensome shim plates to fill the separation between faying surfaces, or other means of remediation in the field, prior to tightening the bolts is eliminated.

The bolted joint connection structure of the present invention also increases construction tolerance for misalignment of components during field steel frame erection because of the slotting of the bolt holes 26A in which some are elongated in a vertical direction and others are slotted in a horizontal direction that is transverse to the longitudinal axis of the beam 19. As a consequence of this construction, the long dimensions of the upper bolts 26 are oriented vertically, and the long dimension of the lower bolts 26 being oriented transverse to a longitudinal direction of the beam 19. The unique direction of slotted bolt holes 26A provides significantly greater shear capacity compared to conventional designs, while significantly reducing misalignment uncertainties during erection. Thus, the need for uncertain reaming of standard bolt holes in the field or the use of oversized bolt holes with slip-critical bolts to accommodate unanticipated field adjustments to the as-built condition is precluded with the bolted joint connection structure 11. Slip-critical bolts are bolts that are typically installed in oversized circular bolt holes that depend on the development of friction forces between clamped faying surfaces to prevent bolt slip through the pre-tensioning of the bolts. Bolts designated as "slip-critical" are typically received through bolt holes having an opening diameter that is about $\frac{3}{16}$ in. larger than the diameter of the bolt. Bolts designated as "slip critical" require costly and restrictive surface-clean conditions, and the use of special primer coatings over defined clamped faying surfaces, and require an independent special inspection for use, which is costly and time consuming. Slip-critical bolts with circular oversized holes also have a

14

significantly reduced load capacity in shear as compared to standard bolts (i.e., bolts received through bolt holes having an opening diameter that is about $\frac{1}{16}$ in. larger than the diameter of the bolt). Thus, a much greater number of slip-critical bolts are required to withstand a given load, as compared to the required number of standard bolts.

Unlike oversized holes requiring the use of slip-critical bolts, the slotted bolt holes 26A are larger than standard bolt holes in only one direction. Also, the slot direction of the bolt holes 26A is perpendicular to the direction of load, that is, does not extend along the longitudinal axis of the beam 19. Instead, the slots of the bolt holes 26A extend perpendicular (broadly, "transverse") to the longitudinal axis of the beam 19 so that when the joint connection structure 11 is loaded, and in particular when the beam is loaded axially along its length or about its major axis in bending, a gap is not formed between the bolts 26 and their respective bolt holes 26A (i.e., no slip of bolt occurs because bolts 26 are already loaded by direct bearing in shear). As used herein "transverse" to the longitudinal axis of the beam 19 means any direction that crosses over the longitudinal axis of the beam and is not parallel to the longitudinal axis of the beam. In some embodiments, the bolt holes 26A have a slotted dimension that is up to about 2.5 times the diameter of the bolt 26. In some embodiments, the bolt holes 26A have a slotted dimension that is from about $\frac{3}{16}$ in. up to about $2\frac{3}{4}$ in. larger than the diameter of the bolt 26. In a preferred embodiment, the bolt holes 26A have a slotted dimension that is about $\frac{3}{4}$ in. larger than the diameter of the bolt 26.

Slotting the bolt holes 26A along the bottom portion of the gusset plates 21 (or in the vertical leg of each lower angle iron 33) provides a longer vertical dimension for the bolt holes to account for any alignment problems that can arise from the bottom flange of the beam 19 being skewed from an exactly perpendicular orientation with respect to the web of the beam and/or the web of the beam not being plumb. Slotting the bolt holes 26A in the cover plate 27 (or the horizontal leg of each of the upper angle irons 31) provides a longer lateral horizontal dimension for the bolt holes to accommodate transverse alignment problems that can arise from the construction of the beam 19. Thus, the unique orientation of slotted bolt holes 26A in the joint connection structure 11 require alignment accuracy in only one out of three possible translational degrees of freedom (i.e., along the longitudinal axis of the beam 19). This is in contrast to having to resolve alignment accuracy challenges in as many as three degrees of freedom using conventional joint connection structures. Greater tolerance for misalignment during the erection of beam 19 and column 15 is achieved with the use of the unique orientation of the slotted bolt holes. Bolts 26 installed in the unique orientation of the slotted bolt holes 26A of this invention also have comparable shear load and bearing capacity to bolts using standard bolt holes, so significantly fewer bolt holes and bolts are required to withstand a given load than would be required if slip-critical bolts were used. According to current industry design standards, the capacity of a bolt received in the slotted bolt hole elongated in the direction(s) prescribed by the present invention provides an increase in shear load capacity of two or more times that provided by slip-critical bolts with circular oversized holes. As a result, the number of bolts required for the joint connection structures, the associated labor costs, and the overall erection time in the field are all decreased.

Conventional joint connection structures typically include bolted connections which orient the bolts that connect the beam assembly to the column assembly so that all the bolts extend along the length of the beam assembly or so that all

the bolts associated with load transfer from beam flanges extend transverse to the length of the beam assembly. These configurations require alignment accuracy in at least two, and as many as three degrees of freedom. The directions of the degrees of freedom include along the longitudinal axis of the beam, a direction along the longitudinal axis of the column, and a direction transverse to the longitudinal axes of the beam and column). The current disclosure of horizontally slotted bolt holes 26A oriented transverse to the longitudinal axis of the beam 19, and the vertically slotted bolt holes 26A configures the joint connection structure 11 so that alignment accuracy is only required in one degree of freedom (i.e., along the longitudinal axis of the beam 19). Thus, alignment accuracy is required only along one axis of the joint connection structure 11. Accordingly, connecting the full-length beam assembly 17 to the column assembly 13 is significantly easier to accomplish in the field.

The unique geometry and stiffness of this all shop fillet-welded and all field-bolted beam-to-column moment-resisting joint connection structure 11 maximizes its performance and the broadness of its design applications, including both extreme wind and moderate-to-severe seismic conditions. In particular, the all field-bolted joint connection structure 11 preserves the physical separation (or gap) between the end of a full-length beam 19 and the flange face of the column 15 made possible by the use of vertically and horizontally extended parallel gusset plates 21 that sandwich the column and the beam similar to prior designs which feature an all field fillet-welded joint connection structure; thus eliminating all of the uncertainty of bending moment load transfer between a rigidly attached steel moment frame beam and column used in the past.

Further, by including the vertically and horizontally extending parallel gusset plates 21 that sandwich both the column 15 and the beam 19, this current all field-bolted joint connection structure 11 preserves the advantage of increased beam-to-column joint stiffness, with a corresponding increase in overall steel moment frame stiffness, which results in smaller beam sizes when the building design is controlled by lateral story drift (not member strength), and hence reduced material costs. When the building design is controlled by member strength (not lateral story drift), this all field-bolted joint connection structure 11 also reduces the beam size and the column size, and hence material quantities and cost, because its connection geometry has no net section reduction in either the beam or the column (i.e., no bolt holes through either the beam or column), thereby maintaining the full strength of the beam and column.

In one aspect of the present disclosure, a full-length beam is connected to gusset plates by bolts so that the full-length beam and gusset plates are substantially free of welded connection. It will be understood that welding the column assembly 13 to the full-length beam assembly 17 is within the scope of that aspect of the disclosure.

Referring to FIGS. 13-24, a beam-to-column moment-resisting joint connection structure of a second embodiment is generally indicated at 111. In the illustrated embodiment, the joint connection joins a column assembly 113 including a column 115 to a full-length beam assembly 117 including a full-length beam 119. The joint connection structure 111 of the second embodiment is substantially identical to the joint connection structure 11 of the first embodiment. Parts of the joint connection structure 111 of the second embodiment corresponding to those of the joint connection structure 11 of the first embodiment will be given the same reference numeral plus "100". This numbering convention is repeated in subsequent embodiments. The joint connection structure

111 further includes a stiffener bar 132 attached to a top surface of cover plate 127 in the joint connection structure 111 and vertical shear plates 128 attached to a web of the beam 119 and bolted to the gusset plates 121 by way of vertical angle irons 134 attached to the vertical shear plates.

The stiffener bar 132 is attached in a suitable manner such as by welds 129 to the top surface of the cover plate 127. In the illustrated embodiment, the stiffener bar 132 is attached to the cover plate 127 between adjacent horizontally spaced bolts 126 received through bolt holes 126A to attach the cover plate to upper angle irons 131. The stiffener bar 132 extends horizontally across the cover plate 127 transverse to a length of the beam 119. Lateral edges of the stiffener bar 132 are flush with longitudinal edges of the cover plate 127. The stiffener bar 132 may be otherwise configured and/or arranged within the scope of the present disclosure. The stiffener bar 132 is optional.

The vertical shear plates 128 are welded or otherwise attached to opposite sides of the web of the beam 119 (FIG. 24). Each of the vertical angle irons 134 is attached in a suitable manner such as by welds 129 at the toe and heel of the leg of the angle iron abutting the web of the beam 119. Bolt holes 126A in the other leg of the angle iron 134 receive bolts 126 extending through corresponding bolt holes 126A in the gusset plate 11 to connect the web of the beam 119 to the gusset plate. In the illustrated embodiment, the bolt holes 126A in the angle iron 134 are slotted in a direction parallel to the length of the beam. The vertical shear plates 128 and angle irons 134 are optional.

Referring to FIGS. 25-36, a beam-to-column moment-resisting joint connection structure of a third embodiment is generally indicated at 211. In the illustrated embodiment, the joint connection joins a column assembly 213 including a column 215 to a full-length beam assembly 217 including a full-length beam 219. The joint connection structure 211 of the third embodiment is substantially identical to the joint connection structure 11 of the first embodiment. The only differences between the two embodiments is cover plate 227 has a closed oblong radiused slot opening 230 extending along the length of the cover plate. It will be understood that the cover plate 227 may have other widths, configurations and slot-type oblong openings. For example, multiple smaller slots may be used in place of a single, larger slot (e.g., slot 230). The smaller slots can be punched out of the cover plate rather than cut out.

Referring to FIGS. 37-48, a beam-to-column moment-resisting joint connection structure of a fourth embodiment is generally indicated at 311. In the illustrated embodiment, the joint connection joins a column assembly 313 including a column 315 to a full-length beam assembly 317 including a full-length beam 319. The joint connection structure 311 of the fourth embodiment is substantially identical to the joint connection structure 211 of the third embodiment. The only difference between the two embodiments is the addition of a stiffener bar 332 attached to a top surface of cover plate 327 in the joint connection structure 311.

Referring to FIGS. 49-60, a beam-to-column moment-resisting joint connection structure of a fifth embodiment is generally indicated at 411. The joint connection structure 411 may be used in the construction of a building framework. In the illustrated embodiment, the joint connection joins a column assembly 413 including a column 415 to a full-length beam assembly 417 including a full-length beam 419.

A spaced apart pair of parallel, vertically and horizontally extending gusset plates 421 sandwich the column 415 and beam 419. Four horizontal shear plates 423 (only three are shown in FIG. 49) are arranged in vertically spaced pairs

generally aligned at top and bottom edges of the gusset plates 421. Two angle irons (broadly, "connecting members") 425A are disposed on an upper flange of the beam 419 at an end of the beam. The angle irons 425A are horizontally spaced from one another and extend along a length of the beam 419. The angle irons 425A connect the gusset plates 421 to the upper flange of the beam 419. The angle irons 425A are L-shaped in cross section. Each angle iron 425A may include a horizontal first leg attached to the upper flange of the beam 419 and a vertical second leg projecting from the first leg perpendicular to the length of the beam. The first leg is attached in a suitable manner such as by a weld 429 between the toe of the first leg and the top surface of the upper flange of the beam 419 and by a weld 429 on the underside of the first leg to the tips of the upper flange. An outer surface of the second leg of each angle iron 425A are bolted to an inner surface of a respective gusset plate 421 by horizontally spaced bolts 426 extending through aligned bolt holes 426A in the second leg of the angle iron and respective gusset plate. Instead of two angle irons 425A for example, a single channel welded to the top flange could be employed.

Two angle irons (broadly, "connecting members") 425B are disposed on a lower flange of the beam 419 at an end of the beam (see, FIGS. 52 and 57). The angle irons 425B are horizontally spaced from one another and extend along a length of the beam 419. The angle irons 425B connect the gusset plates 421 to the lower flange of the beam 419. The angle irons 425B are L-shaped in cross section. Each angle iron 425B may include a horizontal first leg attached to the lower flange of the beam 419 and a vertical second leg projecting from the first leg perpendicular to the length of the beam. The first leg is attached in a suitable manner to the bottom face of the lower flange of the beam 419 such as by a weld 429 between a toe of the first leg and the bottom surface of the lower flange of the beam 419 and a weld 429 between a top surface of the first leg and a tip of the lower flange. An outer surface of the second leg of each angle iron 425B is bolted to an inner surface of a respective gusset plate 421 by horizontally spaced bolts 426 extending through aligned bolt holes 426A in the second leg of the angle iron and respective gusset plate. Instead of two angle irons 425B a single channel welded to the top flange could be employed. Moreover, different combinations of connecting structure could be used. For example, one flange of the beam 419 might use two angle irons, while the other flange of the beam uses a channel.

The bolt holes 426A in the angle irons 425A, 425B may be larger than the bolt holes 426A in the gusset plates 421 to facilitate placement of one or more of the bolts 426 through slightly misaligned holes 426A. In particular, the bolt holes 426A in the gusset plates 421 would be standard size and the bolt holes 426A in the angle irons 425A, 425B would be vertically slotted, and the bolts would be inserted first through the standard sized holes in the gusset plates 421 and then into the slotted bolt holes of the angle irons 425A, 425B. It will be appreciated that similar slotting of one of two mating holes may be used to facilitate bolting the components together in all embodiments may be employed. The bolt connection allows workers in the field to draw the gusset plates 421 into flush engagement with the angle irons 425A, 425B even with the initial gap between the gusset plates and full-length beam assembly 417, without the need of external clamping means.

Referring to FIGS. 57-60, the full-length beam assembly 417 may be fabricated at a fabrication shop prior to being transported to the construction site. To fabricate the full-length beam assembly 417, the angle irons 425A, 425B are

welded at 429 or otherwise attached to the upper and lower flanges of the beam 419. Any welds on the beam assembly needed to form the joint connection structure can be made at the shop. The angle irons 425A, 425B may have other configurations than those illustrated in the current embodiment.

Referring to FIGS. 53-56, the column assembly 413 may also be fabricated at a fabrication shop and later transported to the construction site. To fabricate the column assembly 413, the gusset plates 421 are welded at 429 or otherwise attached to the flanges of the column 415, the optional horizontal shear plates 423 are welded at 429 or otherwise attached to the web of the column and to the top and bottom edges of the gusset plates. Any welds on the column assembly 413 needed to form the beam-to-column moment-resisting joint may be carried out at the shop. The horizontal shear plates 423 can be omitted from the column assembly 413. The gusset plates 421 can have other configurations than those illustrated in the current embodiment. For instance, the gusset plates 421 could have a smaller vertical dimension so that the gusset plates are flush with top and bottom edges of the respective angle irons 425A, 425B rather than extending above and below the angle irons as shown in the illustrated embodiment. The angle irons 425A, 425B may have configurations other than those illustrated in the embodiment.

At the construction site, the column assembly 413 is joined to the full-length beam assembly 417. The column assembly 413 is first erected in a vertical orientation and the end of the full-length beam assembly 417 is positioned horizontally and adjacent to the column assembly, over the gusset plates 421. The full-length beam assembly 417 is then lowered between the gusset plates 421 such that the gusset plates are disposed on opposite sides of the beam 419 and angle irons 425A, 425B of the full-length beam assembly 417. To fixedly secure the two assemblies 413, 417, horizontally spaced bolts 426 are used to attach the gusset plates 421 to the angle irons 425A, 425B through aligned bolt holes in the respective components. Thus, at the construction site, the beam-to-column moment-resisting joint connection structure 411 is completed exclusively through bolt connections. So in the field, the beam-to-column joint connection structure 411 is constructed without the use of welds. The joint connection structure 411 can be used if the building frame is dimensionally close to the exterior curtain wall of the building because the angle irons 425A, 425B are on the inside of the gusset plates 421.

The joint connection structure 411 may also be constructed with a ledger angle 440 (FIG. 52A) attached by the same bolts 426 that attach the column and beam assemblies 413, 417, thus saving material. Only one ledger angle 440 is shown in FIG. 52A. Others would be used in a typical construction, such as a ledger angle like the ledger angle 440 shown, but on the opposite side of the top flange of the beam 419. The bolt 426 that attaches the ledger angle 440 to the assemblies 413, 417 may also attach angle irons 425A to the gusset plates 421. As understood by persons skilled in the art, the ledger is configured to support floor decking (not shown).

Referring to FIGS. 61-72, a beam-to-column moment-resisting joint connection structure of a sixth embodiment is generally indicated at 511. The joint connection structure may be used in the construction of a building framework. In the illustrated embodiment, the joint connection structure 511 joins a column assembly 513 including a column 515 to a full-length beam assembly 517 including a full-length beam 519.

A spaced apart pair of parallel, vertically and horizontally extending gusset plates 521 sandwich the column 515 and end of beam 519. Four optional horizontal shear plates 523 (only three are shown in FIG. 61) are arranged in vertically spaced pairs generally aligned at top and bottom edges of the gusset plates 521. Two angle irons (broadly, "connecting members") 525 are disposed on an upper flange of the beam 519 at an end of the beam. The angle irons 525 are horizontally spaced from one another and extend along a length of the beam 519. The angle irons 525 connect the gusset plates 521 to the upper flange of the beam 519. The angle irons 525 are L-shaped in cross section. Each angle iron 525 may include a horizontal first leg attached to the upper flange of the beam 519 and a vertical second leg projecting upwardly from the first leg transverse to the length of the beam. The angle iron 525 may be attached to the upper flange of the beam 519 in the same way as the angle irons 425A were attached to the upper flange of the beam 419 in the fifth embodiment. An outer surface of the second leg of each angle iron 525 is bolted to an inner surface of a respective gusset plate 521 by horizontally spaced bolts 526 extending through aligned bolt holes 526A in the second leg of the angle iron and respective gusset plate. Instead of two angle irons 525 a single channel welded to the top flange could be employed.

A bottom flange of the beam 519 rests on a cover plate 527 at the end of the beam, which acts as a bearing saddle support for the end of the full-length beam assembly 517. The cover plate 527 is attached in a suitable manner such as by welds 529 to the bottom edge of each gusset plate 521 or near the bottom edges of the gusset plate. The cover plate 527 has a width that is greater than a width of the beam 519 and may be greater than a horizontal spacing of the gusset plates 521. The configuration of the cover plate 527 allows the beam 519 to be lowered between the gusset plates 521 so that the bottom flange of the beam can rest and bear on an upper surface of the cover plate in a self-shoring condition before fixedly securing the beam assembly 517 to column assembly 513. Thus, the beam 519 is fully supported by the column assembly 513 once the end of the beam is placed between the gusset plates 521 onto the top cover plate 527. It will be understood that the cover plate 527 may have other widths within the scope of the present invention. To fixedly secure the beam 519 to the cover plate 527, the bottom flange of the beam is bolted to the upper surface of the cover plate 527 by horizontally spaced bolts 526 extending through aligned bolt holes 526A (see, FIG. 67) in the beam bottom flange and cover plate 527. The bolt holes 526A in the cover plate 527 are larger than the bolt holes 526A in the beam flange to facilitate placement of one or more of the bolts 526 through slightly misaligned holes 526A. In particular, the bolt holes 526A in the beam flange would be standard size and the bolt holes 526A in the cover plate 527 would be oversized (e.g., elongated or oversized diameter) and the bolts would be inserted first through the larger holes into the standard sized holes. The bolt holes 526A in the angle irons 525 may also be larger than the bolt holes 526A in the gusset plates 521. As such, the bolt holes 526A in the gusset plates 521 would be standard size and the bolt holes 526A in the angle irons 525 would be oversized. The component having the oversized hole can be switched or both components may have oversized holes. The bolt connection allows workers in the field to draw the gusset plates 521 into flush engagement with the angle irons 525 and beam 519 even with the initial gap between the gusset plates and full-length beam assembly 517. Moreover, the

lower flange of the beam 519 is drawn flush against the supporting cover plate 527 by the bolts.

FIGS. 64A-64C illustrates some variations for the joint connection structure 511. FIG. 64A shows the beam 519 having bolts 520 either formed as one piece with or fixedly attached as by welding to the bottom surface of the bottom flange of the beam 519. The bolts 520 would be received in the holes in the cover plate 527 when the beam end portion is lowered into place between the gusset plates 521. FIG. 10 64B shows a cover plate 527A received between gusset plates 21 and positioned upward away from a bottom end of the gusset plates. FIG. 64C shows a second lower pair of angle irons 525A located below the upper flange of the beam 519, which are bolted to the top flange of the beam. The 15 horizontal leg of the upper first pair of angle irons 25 is not welded to the top flange of the beam, but rather is also bolted using the bolt that connects the second lower pair of angle irons. In fact, none of the angle irons 525, 525A is welded to the beam. Thus, these bolts that are common to both the 20 first and second pair of angle irons act in double shear to resist bending moments from the beam 519 which doubles the bolt capacity and thereby reduces the number of bolts required. Where feasible, these alternative configurations can be incorporated into the other disclosed embodiments.

Referring to FIGS. 69-72, the full-length beam assembly 517 may be fabricated at a fabrication shop prior to being transported to the construction site. To fabricate the full-length beam assembly 517, the angle irons 525 are welded at 529 or otherwise attached to the upper flange of the beam 519. The bolt holes 526A may also be formed at the shop. Any welding of the beam assembly 517 needed for forming the joint can be done at the shop. Although angle irons 525 are illustrated, other forms of connecting structure may be used, such as a connecting structure having a channel-shaped cross section.

Referring to FIGS. 65-68, the column assembly 513 may also be fabricated at a fabrication shop and later transported to the construction site. To fabricate the column assembly 513, the gusset plates 521 are welded at 529 or otherwise attached to the flanges of the column 515, the horizontal shear plates 523 (if desired) are welded at 529 (FIG. 67) or otherwise attached to the web of the column and to the top and bottom edges of the gusset plates, and the cover plate 527 is welded at 529 or otherwise attached to the bottom edges of the gusset plates. Any welding of the column assembly 511 needed for forming the joint connection structure 513 can be done at the shop. The gusset plates 521 and attached cover plate 527 form a receptacle or saddle support for receiving and supporting the end of the beam assembly 517. The saddle support of the cover plate 527 also provides a permanent spacer to maintain the required separation between the gusset plates 521 during transport to the field, and during erection of the full-length beam assembly to the column assembly. The horizontal shear plates 523 can be omitted from the column assembly 513. The gusset plates 521 and cover plate 527 can have other configurations than those illustrated in the current embodiment.

At the construction site, the column assembly 513 is joined to the full-length beam assembly 517. The column assembly 513 is first erected in a vertical orientation and the end of the full-length beam assembly 517 is positioned adjacent the column assembly, over the gusset plates 521. The full-length beam assembly 517 is then lowered between the gusset plates 521 until the bottom flange of the beam 519 engages the top surface of the cover plate 527. This engagement locates, positions, and supports the end of the full-length beam assembly 517 on the column assembly 513. To

fixedly secure the two assemblies 513, 517, bolts 526 are used to attach the angle irons 525 to the gusset plates 521, and the bottom beam flange to the cover plate 527 through aligned bolt holes 526A in the respective components. Thus, at the construction site, the joint connection structure 511 is completed exclusively through bolt connections. So in the field, the beam-to-column moment resisting joint connection structure 511 is constructed without the use of welds.

FIGS. 64A-64C illustrates some variations for the joint connection structure 511. FIG. 64A shows the beam 519 having bolts 520 either formed as one piece with or fixedly attached as by welding to the bottom surface of the bottom flange of the beam 519. The bolts 520 would be received in the holes in the cover plate 527 when the beam end portion is lowered into place between the gusset plates 521. FIG. 64B shows a cover plate 527A received between gusset plates 21 and positioned upward away from a bottom edges of the gusset plates. FIG. 64C shows a second lower pair of angle irons 525A located below the upper flange of the beam 519, which are bolted to the top flange of the beam. The horizontal leg of the upper first pair of angle irons 525 is not welded to the top flange of the beam, but rather is also bolted using the bolt that connects the second lower pair of angle irons. In fact, none of the angle irons 525, 525A is welded to the beam. Thus, these bolts that are common to both the first and second pair of angle irons act in double shear to resist bending moments from the beam 519 which doubles the bolt capacity and thereby reduces the number of bolts required. Where feasible, these alternative configurations can be incorporated into the other disclosed embodiments.

Referring to FIGS. 73-84, a beam-to-column moment-resisting joint connection structure of a seventh embodiment is generally indicated at 611. In the illustrated embodiment, the joint connection joins a column assembly 613 including a column 615 to a full-length beam assembly 617 including a full-length beam 619.

A spaced apart pair of parallel, vertically and horizontally extending gusset plates 621 sandwich the column 615 and full-length beam 619. Four optional horizontal shear plates 623 (only three are shown in FIG. 73) are arranged in vertically spaced pairs generally aligned at top and bottom edges of the gusset plates 621 as illustrated in the previous embodiments. Vertical flange plates 625 (broadly, "connecting members") are disposed on each side of the beam 619 and attached to the tips of each flange of the beam 619 as by welding at 629. The gusset plates 621 have holes that receive bolts 626 that pass through holes 626A in the flange plates 625. The flange plates 625 facilitate connection of the beam 619 to the gusset plates 621.

Referring to FIGS. 77-80, the column assembly 613 may be fabricated at a fabrication shop and later transported to the construction site. To fabricate the column assembly 613, the gusset plates 621 are welded at 629 or otherwise attached to the flanges of the column 615 and the horizontal shear plates 623 are welded at 629 or otherwise attached to the web of the column and to the top and bottom edges of the gusset plates. Any welds needed on the column assembly 613 for forming the joint can be made at the shop. The horizontal shear plates 623 can be omitted from the column assembly 613. The gusset plates 621 can have other configurations than those illustrated in the current embodiment.

Referring to FIGS. 81-84, the full-length beam assembly 617 may also be fabricated at a fabrication shop prior to being transported to the construction site. To fabricate the full-length beam assembly 617, inner surfaces of the flange plates 625 are welded at 629 or otherwise attached to the flange tips of the beam 619. Separate welds 629 can connect

each flange plate 625 to the top and bottom surfaces of a respective flange of the beam 619. Any welds to the beam assembly 617 needed to form the joint connection structure can be made at the shop. The flange plates 625 and may have other configurations than those illustrated in the current embodiment.

At the construction site, the column assembly 613 is joined to the full-length beam assembly 617. The column assembly 613 is first erected in a vertical orientation and the 10 end of the full-length beam assembly 617 is positioned adjacent the column assembly. The full-length beam assembly 617 is then lowered between the gusset plates 621 such that the gusset plates are disposed on opposite sides of the beam 619 and flange plates 625 of the full-length beam assembly 617. To fixedly secure the two assemblies 613, 617, bolts 626 are used to attach the gusset plates 621 to the flange plates 625 through aligned bolt holes 626A in the respective components. The bolt holes 626A can be slotted as described for prior embodiments of this invention. Thus, 15 20 at the construction site, the joint connection structure 611 is completed exclusively through bolt connections. So in the field, the joint connection structure 611 is constructed without the use of welds. The joint connection structure 611 can be used if the building frame is close to the exterior curtain wall of the building because the flange plates 625 are on the inside of the gusset plates 621.

Referring to FIGS. 85-96, a beam-to-column moment-resisting joint connection structure of an eighth embodiment is generally indicated at 711. In the illustrated embodiment, 30 35 the joint connection joins a column assembly 713 including a column 715 to a full-length beam assembly 717 including a full-length beam 719.

A spaced apart pair of parallel, vertically and horizontally extending gusset plates 721 sandwich the column 715. Four optional horizontal shear plates 723 (only three are shown in FIG. 85) are arranged in vertically spaced pairs generally aligned at top and bottom edges of the gusset plates 721 as illustrated in the previous embodiments. A channel-shaped end plate 725 (broadly, "a connecting member") is disposed 40 45 on an axially facing end of the beam 719. The end plate 725 provides a connection of the full-length beam 719 to the gusset plates 721. The end plate 725 may include a first leg, at least a portion of which engages an outer surface of one of the gusset plates 721 and extends along the vertical dimension of the gusset plate, a connecting section extending transversely from the first leg toward the other gusset plate 721, and a second leg extending from the connecting section, at least a portion of which engages an outer surface of the other gusset plate 721 and extends along the vertical dimension of the other gusset plate. The connecting section of the end plate 725 is attached in a suitable manner such as by welds 729 to the axially facing end of the beam 719. The first and second legs of the end plate 725 are bolted to the outer surface of respective gusset plates 721 by vertically spaced bolts 726 extending through aligned bolt holes 726A in the first and third legs of the end plate 725 and gusset plates 721. The bolts 726 straddle beam flanges to provide access to the bolts from either the top or bottom of the flanges.

Referring to FIGS. 89-92, the column assembly 713 may be fabricated at a fabrication shop and later transported to the construction site. To fabricate the column assembly 713, the gusset plates 721 are welded at 729 or otherwise attached to the flanges of the column 715 and the optional horizontal shear plates 723 are welded at 729 or otherwise attached to the web of the column and to the top and bottom edges of the gusset plates. Any welds on the column assembly 713

needed to form the joint can be carried out at the shop. The horizontal shear plates 723 can be omitted from the column assembly 713. The gusset plates 721 can have other configurations than those illustrated in the current embodiment.

Referring to FIGS. 93-96, the full-length beam assembly 717 may also be fabricated at a fabrication shop prior to being transported to the construction site. To fabricate the full-length beam assembly 717, an outer surface of the connecting section of the end plate 725 is welded at 729 or otherwise attached to the end of the beam 719. In a preferred embodiment, the end plate 725 is groove welded to the beam 719. Any welds on the beam assembly 717 needed to form the joint can be made at the shop. For instance, the welds could be fillet welds or stitch welds. The end plate 725 may have other configurations than illustrated in the current embodiment.

At the construction site, the column assembly 713 is joined to the full-length beam assembly 717. The column assembly 713 is first erected in a vertical orientation and the end of the full-length beam assembly 717 is positioned horizontally and adjacent to the column assembly. The full-length beam assembly 717 is then moved toward the gusset plates 721 such that the first and second legs of the end plate 725 sandwich portions of the gusset plates. To fixedly secure the two assemblies 713, 717, bolts 726 are used to attach the gusset plates 721 to the end plate 725 through aligned bolt holes 726A in the respective components. Thus, at the construction site, the beam-to-column moment-resisting joint connection structure 711 is completed exclusively through bolt connections. So in the field, the joint connection structure 711 is constructed without the use of welds. Some or all of the bolt holes 726A can be oversized to reduce alignment constraints in connecting the full length beam assembly 717 to the column assembly 713.

Referring to FIGS. 97-108, a beam-to-column moment-resisting joint connection structure of a ninth embodiment is generally indicated at 811. In the illustrated embodiment, the joint connection joins a column assembly 813 including a column 815 to a full-length beam assembly 817 including a full-length beam 819.

A spaced apart pair of parallel, vertically and horizontally extending gusset plates 821 sandwich the column 815 and an end portion of the beam 819. Four optional horizontal shear plates 823 (only three are shown in FIG. 97) are arranged in vertically spaced pairs generally aligned at top and bottom edges of the gusset plates 821 as illustrated in the previous embodiments. A first mounting plate 825 (broadly, "a connecting member") is disposed on an axially facing end of the beam 819. The first mounting plate 825 facilitates connection of the beam 819 to the gusset plates 821 as will be explained in greater detail below. The first mounting plate 825 is attached in a suitable manner such as by welds 829 to the axially facing end of the beam 819. A second mounting plate 827 (broadly, "a connecting member") extends between the gusset plates 821. The second mounting plate 827 is attached in a suitable manner such as by welds 829 to the gusset plates 821. The first mounting plate 825 is bolted to the second plate 827 by bolts 826 extending through aligned bolt holes 826A in the first and second plates. The mounting plate 827 is attached to the gusset plates 821 such that a gap 828 is formed between the mounting plate 827 and an axially facing end of the adjacent column flange.

Referring to FIGS. 101-104, the column assembly 813 may be fabricated at a fabrication shop and later transported to the construction site. To fabricate the column assembly 813, the gusset plates 821 are welded at 829 or otherwise attached to the flanges of the column 815, the optional

horizontal shear plates 823 are welded at 829 or otherwise attached to the web of the column and to the top and bottom edges of the gusset plates, and the second mounting plate 827 is welded at 829 or otherwise attached to inner surfaces 5 of the horizontally extended gusset plates. Any welding on the column assembly 813 needed to form the joint connection structure can be carried out at the shop. The horizontal shear plates 823 can be omitted from the column assembly 813. The gusset plates 821 and second mounting plate 827 10 can have other configurations than those illustrated in the current embodiment.

Referring to FIGS. 105-108, the full-length beam assembly 817 may also be fabricated at a fabrication shop prior to being transported to the construction site. To fabricate the full-length beam assembly 817, an inner surface of the first mounting plate 825 is welded at 829 or otherwise attached to the end of the full-length beam 819. Thus, at the shop, the full-length beam assembly 817 is constructed exclusively by welds. The first mounting plate 825 may have other configurations than illustrated in the current embodiment.

At the construction site, the column assembly 813 is joined to the full-length beam assembly 817. The column assembly 813 is first erected in a vertical orientation and the end of the full-length beam assembly 817 is positioned horizontally and adjacent to the column assembly. The full-length beam assembly 817 is then moved either vertically up or down into position between the gusset plates 821 such that the gusset plates are disposed on opposite sides of the beam 819 and the first and second mounting plates 825, 827 are in opposing relation. To fixedly secure the two assemblies 813, 817, bolts 826 are used to attach the first mounting plate 825 to the second mounting plate 827 through aligned bolt holes 826A, 826A in the respective components. It is possible to oversize the bolt holes 826A to reduce alignment constraints. Thus, at the construction site, the beam-to-column moment-resisting joint connection structure 811 is completed exclusively through bolt connections. So in the field, the joint connection structure 811 can be constructed without the use of welds.

The configuration and position of the adjacent mounting plates 825, 827 and bolts 826 counteract bending moments that can be placed on the full-length beam 819 after the building framework is erected. As previously mentioned, loads on the building framework can cause the beam 819 to flex up and/or down generally about a horizontal axis extending perpendicular to the length of the beam. As the beam 819 flexes up and/or down about the axis, the bolts 826 are placed in tension and/or compression. This flexing may be cyclical. This is a result of the mounting plates 825, 827 and in particular the bolt holes 826A in the plates being arranged to receive the bolts 826 in an orientation where the bolts extend along a length of the beam 819, thereby acting in tension or compression to resist the bending moment applied by the full-length beam. This is different from other joint connection structures, such as the joint connection structures 11, 111, 211, 311, 411, 511, 611, 711 described herein that position the bolts to extend transverse to the length of the beam, thereby acting in shear.

Referring to FIGS. 109-120, a beam-to-column moment-resisting joint connection structure of a tenth embodiment is generally indicated at 911. The joint connection structure may be used in the construction of a building framework. In the illustrated embodiment, the joint connection joins a column assembly 913 including a column 915 to a full-length beam assembly 917 including a full-length beam 919.

A spaced apart pair of parallel, vertically and horizontally extending gusset plates 921 sandwich the column 915 and an

end portion of the beam 919. Four optional horizontal shear plates 923 (only three are shown in FIG. 109) are arranged in vertically spaced pairs generally aligned at top and bottom edges of the gusset plates 921. Two horizontal cover plates 927A, 927B are arranged in a vertically spaced pair sandwiching the end portion of the full-length beam 919. Bottom cover plate 927B is optional. Upper cover plate 927A may have a width that is greater than a width of the beam 919 and wider than a horizontal spacing of the gusset plates 921. Lower cover plate 927B may have a width that is less than the horizontal spacing between the gusset plates 921. The configuration of the cover plates 927A, 927B allows the beam 919 to be lowered between the gusset plates 921 so that the upper cover plate 927A rests on the top edge of the gusset plates before fixedly securing the beam assembly 917 to column assembly 913 via the gusset plates 921 as will be explained in greater detail below. It will be understood that the cover plates 927A, 927B may have other widths relative to each other within the scope of the present disclosure.

Referring to FIGS. 109-116, each gusset plate 921 may have a plurality of lugs 931A (broadly, “connecting members”) attached to an outer surface of the gusset plate generally at a top of the gusset plate and attached to an inner surface of the gusset plate generally at a bottom of the gusset plate. Alternately, both top and bottom lugs may be cast as an integral part of separate longitudinal steel strip plates (not shown) that may be individually welded or otherwise attached to the corresponding faces of the gusset plate 921. The lugs 931A comprise cuboidal members welded at 922 to the gusset plates 921, or cast as an integral part of a longitudinal steel strip plate which may be welded or otherwise attached to the gusset plates. The lugs 931A have holes 933A (FIG. 116) for receiving bolts 926 as will be explained in greater detail below. In the illustrated embodiment, a plurality of lugs 931A (three are shown) are welded at 922 to the outer surface of each the gusset plate 921 at the top of the gusset plate, and a plurality of lugs 931A (three) are welded at 922 to the inner surface of each gusset plate at the bottom of the gusset plate. Each set of lugs 931A is horizontally spaced and vertically aligned such that the holes 933A of the lugs 931A in each set are disposed on a common axis extending along a horizontal length of the gusset plates 921.

Referring to FIGS. 109-112 and 117-120, each cover plate 927A, 927B may have a plurality of lugs 931B (broadly, “connecting members”) attached to a bottom surface of the cover plate. The lugs 931B may comprise cuboidal members welded at 922 or otherwise attached to the cover plates 927A, 927B. If cover plate 927B is omitted, bottom lugs 931B can be welded or otherwise attached to the bottom face of the beam bottom flange, or may be cast as an integral part of a longitudinal steel strip plate that is welded or otherwise attached to the bottom face of the bottom beam flange. The lugs 931B have holes 933B (FIG. 120) for receiving the bolts 926 as will be explained in greater detail below. In the illustrated embodiment, two sets of three lugs 931B are welded at 922 to opposite sides of the bottom surface of each cover plate 927A, 927B. Each set of three lugs 931B is horizontally spaced along a length of the cover plate 927A, 927B and aligned such that the holes 933B of the lugs 931B in each set are disposed on a common axis extending along the length of the respective cover plate 927A, 927B and along a length of the beam 919. The cover plates 927A, 927B are welded at 929 or otherwise attached to respective upper and lower flanges of the beam 919.

Referring to FIG. 113, the column assembly 913 may be fabricated at a fabrication shop and later transported to the

construction site. To fabricate the column assembly 913, the gusset plates 921 are welded at 929 or otherwise attached to the flanges of the column 915 and the horizontal shear plates 923 are welded at 929 or otherwise attached to the web of the column and to the top and bottom edges of the gusset plates. Any welding needed on the column assembly 913 to form the beam-to-column joint may be carried out by the shop. The horizontal shear plates 923 can be omitted from the column assembly 913. The gusset plates 921 and lugs 931A can have other configurations than those illustrated in the current embodiment. Moreover, the number of lugs 931A can be other than three.

Prior to attaching the gusset plates 921 to the column 915, the lugs 931A are secured to the gusset plates. The lugs 931A are secured to the gusset plates 921 by welding at 922 each individual lug directly to the surface of the gusset plate as shown in the illustrated embodiment. Alternatively, the lugs 931A can be grouped using a common cast steel strip plate (not shown). Still further, the lugs 931A can be modularly set in place on a longitudinal steel strip plate (not shown) and welded to the plate. The longitudinal steel strip plate can then be welded or otherwise attached to the gusset plate 921. This provides a greater weld surface area for a more secure weld and may allow for greater accuracy in placement of the lugs 931A. The lugs 931A may also be secured to the gusset plates 921 by casting the lugs with the gusset plates. Other means of securing the lugs 931A to the gusset plates 921 are envisioned.

Referring to FIG. 117, the full-length beam assembly 917 may be fabricated at a fabrication shop prior to being transported to the construction site. To fabricate the full-length beam assembly 917, the cover plates 927A, 927B are welded at 929 or otherwise attached to the upper and lower flanges, respectively, of the full-length beam 919. Any welding needed on the full-length beam assembly 917 to form the joint may be carried out at the shop. The cover plates 927A, 927B may have other configurations than those illustrated in the current embodiment.

Prior to attaching the cover plates 927A, 927B to the full-length beam 919, the lugs 931B are secured to the cover plates. The lugs 931B are secured to the cover plates 927A, 927B by welding at 922 or otherwise attaching each individual lug directly to the surface of the cover plate as shown in the illustrated embodiment. Alternatively, the lugs 931B can be modularly set in place on a longitudinal steel strip plate (not shown) and welded or otherwise attached to the plate, which can then be welded to the cover plates 927A, 927B. As mentioned above, this provides a greater weld surface area for a more secure weld and potentially more accurate location of the lugs 931B. The lugs 931B may also be secured to the cover plates 927A, 927B by casting the lugs with the cover plates. If cover plate 927B is omitted, the lugs 931B can be cast as an integral part of a longitudinal steel strip plate that may be welded or otherwise attached to the corresponding top or bottom beam flange. Other means of securing the lugs 931B to the cover plates 927A, 927B are envisioned.

At the construction site, the column assembly 913 is joined to the full-length beam assembly 917. The column assembly 913 is first erected in a vertical orientation and the end of the full-length beam assembly 917 is positioned adjacent the column assembly, over the gusset plates 921. The full-length beam assembly 917 is then lowered between the gusset plates 921 until the bottom surface of the upper cover plate 927A engages the upper edges of the gusset plates. This engagement temporarily locates and supports the full-length beam assembly 917 on the column assembly

913. When the beam assembly 917 is lowered into engagement with the column assembly 913, the lugs 931B on the cover plates 927A, 927B are located adjacent to respective lugs 931A on the gusset plates 921 so that the holes 933A, 933B in the lugs 931A, 931B, respectively, are aligned. To fixedly secure the two assemblies 913, 917, bolts 926 are inserted through the aligned holes 933A, 933B in the respective components. The holes 933B in the lugs 931B are oversized to facilitate threading the bolt 926 through holes 931B and 931A, and to ensure that bolts 926 can only act in tension or compression and thus provide higher both capacity. It will be understood that it could be the holes 933A in the lugs 931A that are oversized. Thus, at the construction site, the joint connection structure 911 is completed exclusively through bolt connections. So in the field, the joint connection structure 911 is constructed without the use of welds.

The configuration and position of the lugs 931A, 931B and bolts 926 counteract bending moments that can be placed on the full-length beam 919 after the building framework is erected. Loads on the building framework can cause the beam 919 to flex up and/or down generally about a horizontal axis extending perpendicular to the length of the beam. As the beam 919 flexes up and/or down about the horizontal axis, the bolts 926 are placed in tension and/or compression. This loading may be cyclical. This is a result of the holes 933A, 933B of the lugs 931A, 931B, respectively, being arranged to receive the bolts 926 in an orientation where the bolts extend along a length of the beam 919. This is unlike other bolted joint connection structures of the current disclosure, such as the joint connection structures 11, 111, 211, 311, 411, 511, 611, 711 described herein, which positions the bolts to extend transverse to the length of the beam, so that the bolts are loaded in shear thereby minimizing the load capacity of the bolts. In contrast, in the current embodiment the loading in bolts 926 occurs in tension or compression, which maximizes the capacity of the bolts, allowing a fewer number of bolts to be employed. It is also envisioned that bearings (not shown) instead of lugs can be used.

Referring to FIGS. 121-132, a beam-to-column moment-resisting joint connection structure of an eleventh embodiment is generally indicated at 1011. The joint connection structure may be used in the construction of a building framework. In the illustrated embodiment, the joint connection joins a column assembly 1013 including a column 1015 to a full-length beam assembly 1017 including a full-length beam 1019.

A spaced apart pair of parallel, vertically and horizontally extending gusset plates 1021 sandwich the column 1015 and beam 1019. Four horizontal shear plates 1023 (only three are shown in FIG. 121) are arranged in vertically spaced pairs generally aligned at top and bottom edges of the gusset plates 1021. Vertical shear plates 1028 are welded at 1029 to a web of the beam 1019 and bolted to the gusset plates 1021 by way of vertical angle irons 1025 attached to the vertical shear plates. The vertical angle irons 1025 are L-shaped in vertical plan view. Each vertical angle iron 1025 may include a vertically extending first leg welded to the a corresponding vertical shear plate 1028 and a second vertically extending leg projecting perpendicular to the first leg along the length of the beam. An outer surface of the second leg of each angle iron 1025 is bolted to an inner surface of a respective gusset plate 1021 by vertically spaced bolts 1026 extending through aligned bolt holes 1026A in the second leg of the angle iron and respective gusset plate. A horizontal cover plate 1027 is located on a top surface of an

upper flange of the beam 1019 and is attached in a suitable manner as by welding to tips of the upper flange. Cover plate 1027 may have a width that is greater than a width of the beam 1019 and greater than a horizontal spacing of the gusset plates 1021. Lower angle irons 1033 are each attached in a suitable manner such as by welds 1029 to a bottom surface of a lower flange of the beam 1019 and to a tip of the lower flange. The spacing between laterally outwardly facing surfaces of vertical legs of the angle irons 1033 is less than the horizontal spacing between the gusset plates 1021. The configuration of the cover plate 1027 and angle irons 1033 allows the beam 1019 to be lowered between the gusset plates 1021 so that the cover plate 1027 rests on the top edge of the gusset plates before fixedly securing the beam assembly 1017 to column assembly 1013 via the gusset plates 1021 as will be explained in greater detail below. It will be understood that the other sizes and arrangements of the cover plate 1027 and angle irons 1033 are possible. For example, the angle irons 1033 can be attached to a lower cover plate (not shown) that is attached to the lower flange of the beam 1019.

Referring to FIGS. 121-128, each gusset plate 1021 may have an upper angle iron 1031 (broadly, “an upper connecting member”) attached to an outer surface of the gusset plate. The upper angle iron 1031 may comprise an elongate L-shaped member including a vertical first leg attached to the outer surface of the gusset plate at an upper portion of the gusset plate and extending horizontally along the upper portion of the gusset plate. The first leg of each upper angle iron 1031 may be welded or otherwise attached to the outer surface of the respective gusset plate 1021. A horizontal second leg of the upper angle iron 1031 may project transversely from the first leg of the upper angle iron and laterally away from the gusset plate 1021 and away from the beam 1019. In the illustrated embodiment, the first and second legs of the upper angle irons 1031 are disposed at substantially a right angle to each other. A top surface of the second leg of each upper angle iron 1031 is bolted to a bottom surface the cover plate 1027 by horizontally spaced bolts 1026 extending through aligned bolt holes 1026A in the second leg of the upper angle irons and upper cover plate. In the illustrated embodiment, the upper angle irons 1031 are configured such that the lateral edge of the second legs are flush with the lateral edges of the cover plate 1027 (FIG. 124). Further, the top surface of the second leg of the upper angle irons 1031 are above the top edge of the gusset plates 1021. In another embodiment, the second leg of at least one of the upper angle irons 1031' may extend laterally past a lateral edge of the cover plate 1027 (FIG. 133). This configuration of the upper angle iron 1031' may provide a support surface for a component such as a metal floor decking 1035 to rest on top of the upper angle iron. The upper angle irons 1031, 1031' may be otherwise configured and/or arranged within the scope of the present invention.

Referring to FIGS. 129-132, the lower angle irons 1033 (broadly, “lower connecting members”) comprise elongate L-shaped members including a first leg attached to the bottom surface lower flange of the beam 1019 at opposite side portions of the lower flange and extending horizontally along the side portions. The first leg of each lower angle iron 1033 may be welded or otherwise attached to the bottom surface of the lower flange of the beam 1019. Each lower angle iron 1033 may also include a second leg projecting transversely from the first leg of the lower angle iron and downward, away from the lower flange. In the illustrated embodiment, the first and second legs of each lower angle iron 1033 are disposed at substantially a right angle to each

other. An outer surface of the second leg of each lower angle iron 1033 is bolted to an inner surface of a respective gusset plate 1021 by horizontally spaced bolts 1026 extending through aligned bolt holes 1026A in the second leg of the lower angle iron and the gusset plate. The bolt holes 1026A in the various components may be slotted as shown in the first embodiment to facilitate alignment. Other arrangements to reduce alignment constraints are possible. Referring to FIG. 129-132, the full-length beam assembly 1017 may be fabricated at a fabrication shop prior to being transported to the construction site. To fabricate the full-length beam assembly 1017, the angle irons 1025 are welded or otherwise attached to the web of the beam 1019, the cover plate 1027 is welded or otherwise attached to the upper flange of the beam, and the lower angle irons 1033 are welded or otherwise attached to the lower flange of the beam. Thus, at the shop, the full-length beam assembly 1017 is constructed exclusively by welds. The angle irons 1025, cover plate 1027 and lower angle iron 1033 may have other configurations than those illustrated in the current embodiment.

Referring to FIG. 125-128, the column assembly 1013 may also be fabricated at a fabrication shop and later transported to the construction site. To fabricate the column assembly 1013, the gusset plates 1021 are welded or otherwise attached to the flanges of the column 1015, the horizontal shear plates 1023 are welded or otherwise attached to the web of the column and to the top and bottom edges of the gusset plates, and the upper angle arms 1031 are welded or otherwise attached to the gusset plates. Thus, at the shop, the column assembly 1013 is constructed exclusively by welds. The horizontal shear plates 1023 can be omitted from the column assembly 1013. The gusset plates 1021 and upper angle irons 1031 can have other configurations than those illustrated in the current embodiment.

At the construction site, the column assembly 1013 is joined to the full-length beam assembly 1017. The column assembly 1013 is first erected in a vertical orientation and the end of the full-length beam assembly 1017 is positioned adjacent the column assembly, over the gusset plates 1021. The full-length beam assembly 1017 is then lowered between the gusset plates 1021 until the bottom surface of the cover plate 1027 engages the top surface of the second leg of the upper angle irons 1031. This engagement temporarily locates and supports the full-length beam assembly 1017 on the column assembly 1013. To fixedly secure the two assemblies 1013, 1017, bolts 1026 are used to attach the upper angle irons 1031 to the cover plate 1027, the lower angle irons 1033 to the gusset plates 1021, and the vertical angle irons 1025 to the gusset plates through aligned bolt holes 1026A in the respective components. Thus, at the construction site, the joint connection structure 1011 is completed exclusively through bolt connections. So in the field, the joint connection structure 1011 is constructed without the use of welds.

Referring to FIGS. 134-136, a beam-to-column moment-resisting joint connection structure of a twelfth embodiment is generally indicated at 1111. In the illustrated embodiment, the joint connection joins a column assembly 1113 including a column 1115 to a full-length beam assembly 1117 including a full-length beam 1119. The joint connection structure 1111 of the twelfth embodiment is substantially identical to the joint connection structure 11 of the first embodiment. The primary difference between the two embodiments is gusset plates 1121 are bolted to the column 1115. In particular, a pair of vertical angle irons 1124A are welded at 1129 to each flange 1116 of the column 1115 (only three can be seen in the Figures) and a pair of horizontal angle irons

1124B are welded at 1129 to opposite sides of the web of the column (only two). The vertical angle irons 1124A are elongate L-shaped members. Each vertical angle iron 1124A may include a vertically extending first leg welded to the a flange 1116 of the column 1115 and a second vertically extending leg projecting perpendicular to the first leg transverse to the length of the column. An outer surface of the second leg of each vertical angle iron 1124A is bolted to an inner surface of a respective gusset plate 1121 by vertically spaced bolts 1126 extending through aligned bolt holes in the second leg of the vertical bracket and respective gusset plate.

The horizontal angle irons 1124B are also elongate L-shaped members. Each horizontal angle iron 1124B may include a horizontally extending first leg welded to a web of the column 1115 and a second horizontally extending leg projecting perpendicular to the first leg along the length of the column. An outer surface of the second leg of each horizontal angle iron 1124B is bolted to an inner surface of a respective gusset plate 1121 by vertically spaced bolts 1126 extending through aligned bolt holes in the second leg of the horizontal angle iron and respective gusset plate. The angle irons 1124A, 1124B can have other configurations without departing from the scope of the disclosure.

Referring to FIGS. 137-139, a beam-to-column moment-resisting joint connection structure of a thirteenth embodiment is generally indicated at 1211. In the illustrated embodiment, the joint connection joins a column assembly 1213 including a column 1215 to a full-length beam assembly 1217 including a full-length beam 1219. The joint connection structure 1211 of the thirteenth embodiment is substantially identical to the joint connection structure 1111 of the twelfth embodiment except vertical brackets 1224A are rectangular plate members rather than angle irons 1124A. However, brackets 1224A, 1224B can have other configurations without departing from the scope of the disclosure.

Referring to FIGS. 140-157, a beam-to-column moment-resisting joint connection structure of a fourteenth embodiment is generally indicated at 1311. The joint connection joins a pre-fabricated column assembly 1313 including a column 1315 having a longitudinal axis (e.g., a substantially vertical longitudinal axis) and a pre-fabricated full-length beam assembly 1317 including a full-length beam 1319. The beam assembly may be less than "full length" within the scope of the present invention. The joint connection structure 1311 does not require any bolts or welds to connect the column assembly 1313 and the full length beam assembly 1317 to one another. Instead, the joint connection structure 1311 includes a connection system 1312 that allows the column assembly 1313 and beam assembly 1317 to be connected to one another in a manner that prevents movement of the beam assembly 1317 relative to the column assembly 1313 without using any bolts or welds to join the column assembly 1313 to the full length beam assembly 1317. The connection system 1312 is structured and arranged so the column assembly 1313 and beam assembly 1317 can be positioned relative to one another in an interlocked configuration to form the joint connection structure 1311. This saves time and expense associated with connecting the column assembly 1313 and beam assembly 1317 at the construction site. The load transfer mechanism for resisting the applied moment, axial load and vertical load from the full length beam assembly 1317 to the column assembly 1313 is direct bearing between interlocking bearing elements 1314, 1324, described more fully hereinafter. Load transfer through direct bearing is the most efficient and

positive way to provide a beam-to-column moment-resisting connection joint structure, while saving time and expense associated with connecting the column assembly 1313 and the beam assembly 1317 at the construction site as compared to field welding or field bolting.

Referring to FIGS. 140 and 146, the column assembly 1313 includes a pair of gusset plates 1321 connected to the column 1315 on opposite sides of the column. The gusset plates 1321 extend laterally outward from the column 1315. The gusset plates 1321 are configured to receive the beam 1319 of the full length beam assembly 1317 therebetween during connection of the beam assembly to the column assembly 1313. Plural bearing elements 1314 are operatively connected to each gusset plate 1321. In the illustrated embodiment, there are a plurality of bearing elements 1314 (e.g., 11 bearing elements) on each gusset plate 1321. Each of the bearing elements 1314 projects from the respective gusset plate 1321. For example, some of the bearing elements 1314 in the illustrated embodiment project outwardly from the respective gusset plate 1321 (i.e., away from the opposing gusset plate on the opposite side of the column 1315). Others of the bearing elements 1314 project inwardly from the respective gusset plate (i.e., inwardly toward the opposing gusset plate on the opposite side of the column). Each bearing element 1314 has one or more exterior bearing engagement surfaces 1316 positioned to engage the beam assembly 1317 in a manner that limits movement of the full length beam assembly 1317 relative to the column assembly 1313, as will be explained in more detail below.

The bearing elements 1314 can be secured to the gusset plates 1321 of the column assembly 1313 in several different ways. For example, the bearing elements 1314 may be secured to the gusset plates 1321 by one or more welds. In the illustrated embodiment (see FIG. 146), the bearing elements 1314 are attached to one or more mounting plates 1320 (e.g., 3 mounting plates 1320A, 1320B, 1320C), which are secured to each of the gusset plates 1321. For instance, in the illustrated embodiment two mounting plates 1320A, 1320C are secured to the outer surface of each gusset plate 1321 and another mounting plate 1320B is secured to the inner surface of each gusset plate. In particular, as illustrated, each gusset plate 1321 has one mounting plate 1320A secured so it extends along an upper edge of the outer surface of the gusset plate and another mounting plate 1320B secured so it extends along a lower edge of the inner surface of the gusset plate. Each gusset plate 1321 also has a mounting plate 1320C secured so it extends along a side edge of the outer surface of the gusset plate 1321 at a location spaced away from the column 1315. The mounting plates 1320A, 1320B, and 1320C are suitably secured to the gusset plates 1321 by one or more welds 1322. The mounting plates 1320 are suitably positioned so they do not extend all the way to the nearest edge of the gusset plates 1321.

A plurality of the bearing elements 1314 are secured to each of the mounting plates 1320. Each of the mounting plates 1320 suitably has a width that is slightly greater than the width of the bearing elements 1314. The bearing elements 1314 for each mounting plate 1320 are suitably arranged in a linear, spaced configuration on the mounting plate, leaving spaces 1330 between the adjacent bearing elements. The bearing elements 1314 are suitably welded to the mounting plates 1320 of the column assembly 1313 by a pair of welds 1318 along two parallel sides of the bearing element, and in turn the mounting plates are connected by welds 1322 to the gusset plates 1321 (see FIGS. 144-145). Although it is possible to use additional welds to secure each bearing element 1314 to the respective mounting plate 1320,

this welding configuration has the advantage that there are no welds in the spaces 1330 between adjacent bearing elements 1314 on any of the mounting plates 1320. The absence of flux material associated with the welds 1318 in the spaces 1330 between the bearing elements 1314 can be helpful when it comes time to connect the column assembly 1313 and beam assembly 1317, as will become apparent. Although the bearing elements can be welded directly to the gusset plate if desired, it can be easier to achieve precise spacing between the bearing elements 1314 by first welding several bearing elements 1314 to a mounting plate 1320 and then welding the mounting plate, with the bearing elements already thereon, to the gusset plate 1321 or other structure of the joint connection structure 1311. Similarly, the bearing elements can be formed as one-piece with the mounting plate (e.g., in a casting process or an industrial scale three dimensional printing process), which can also provide high precision in the positioning of the bearing elements more easily and more certainly than welding each bearing element directly to the gusset plate.

Each bearing element 1314 is suitably a solid block of material (e.g., steel). It is not necessary to include any bores or other void areas in the bearing elements 1314 because it is not necessary to extend any bolts or other fasteners through the bearing elements. The bearing elements 1314 are suitably substantially rectangular blocks (e.g., have a cuboidal shape), as illustrated in FIGS. 140, 141, and 144. However, if desired the bearing elements may have other suitable shapes, such as a tapered, trapezoidal prism shape as is the case with the bearing elements 1314' illustrated in FIG. 144A. The tapered prismatic bearing elements 1314' are oriented so the space 1330 between adjacent bearing elements 1314' is larger at the top of the space than it is at the bottom. Similarly, the narrowest parts of the interlocking bearing elements 1324' on the beam assembly 1317 are at the bottom. This can help the beam assembly 1317 to align with the bearing elements 1314' on the column assembly 1313 as the full length beam assembly is lowered into connection with the column assembly. Initially, the narrowest parts of the bearing elements 1324' of the beam assembly 1317 are received in the widest parts of the spaces 1330 defined between adjacent bearing elements 1314' of the column assembly 1313. The tapered surfaces of the bearing elements 1314', 1324' can draw the full length beam assembly 1317 into better alignment as the beam assembly is lowered and engages with the column assembly 1313.

Referring to FIGS. 151-157, the pre-fabricated full length beam assembly 1317 includes a plurality of bearing elements 1324 operatively attached to the beam 1319 in spaced apart arrangement for receiving and interlocking with corresponding bearing elements 1314 on the column assembly 1313 therebetween for moment connecting the full length beam assembly to the column assembly 1313. As illustrated, the beam 1319 of the full length beam assembly 1317 includes upper and lower flanges 1332, 1334 and a substantially vertical web 1336 extending therebetween and connecting the upper and lower flanges to one another. An upper cover plate 1323 (broadly, a connecting member) is secured (e.g., welded) to the upper surface of the upper flange 1332 at one end of the beam 1319. A lower cover plate 1325 (broadly, a connecting member) is secured to (e.g., welded to) the lower surface of the lower flange 1334 at the same end of the beam 1319 as the upper cover plate 1323. The beam 1319 has a longitudinal axis that is substantially perpendicular to the longitudinal axis of the column 1315 in the joint connection structure 1311. The end portion of the beam 1319 to which the cover plates 1323, 1325 are secured

is received between the gusset plates 1321 of the column assembly in the joint connection structure 1311, as illustrated in FIG. 140. When the beam assembly 1317 is connected to the column assembly 1313, the upper cover plate 1323, which is wider than the lower cover plate 1325 and wider than the distance between the gusset plates 1321, extends over and beyond the upper edges of the gusset plates. The lower cover plate 1325 suitably has a width that is slightly less than the distance between the gusset plates 1321 and is positioned between the gusset plates near their lower ends in the joint connection structure 1311. As illustrated in FIG. 143, the lower cover plate 1325 suitably spans substantially the entire distance between the inner surfaces of the gusset plates 1321 in the joint connection structure 1311.

The full length beam assembly 1317 includes bearing elements 1324 operatively connected to the beam 1319. The bearing elements 1314 of the column assembly 1313 are attached to the gusset plates 1321 in spaced apart arrangement for receiving and interlocking with corresponding bearing elements 1324 on the full length beam assembly 1317 for moment connecting the beam assembly to the column assembly. In the illustrated embodiment, the beam assembly 1317 has a plurality of bearing elements 1324. Each bearing element 1324 has one or more exterior bearing engagement surfaces 1326 positioned to engage the column assembly 1313 in a manner that will be explained in more detail below. In the illustrated embodiment, the bearing elements 1324, include sets of bearing elements projecting downwardly from opposite sides of the upper cover plate 1323, sets of bearing elements projecting downwardly from the lower cover plate 1325, and sets of bearing elements projecting laterally from the web 1336 of the beam 1319.

The bearing elements 1324 can be secured to the full length beam assembly 1317 in several different ways without departing from the scope of the invention. As illustrated in FIG. 152, for example, the bearing elements 1324 that project downwardly from the upper cover plate 1323 are mounted on mounting plates 1320D (only one of which is visible in FIG. 152) and the bearing elements that project downwardly from the lower cover plate 1325 are mounted on mounting plates 1320E. The mounting plates 1320D, 1320E are suitably identical to the mounting plates 1320A, 1320B, 1320C described above. Alternatively, the bearing elements of the beam assembly can be secured directly to the respective cover plate by one or more welds. Further, the bearing elements can be formed as one-piece with the respective mounting plate (e.g., in a casting process or industrial scale three dimensional printing process). The bearing elements 1324 can be secured by welds 1328 (see FIGS. 144-145) extending along two parallel sides, as described above for the bearing elements 1314 of the column assembly 1313 so that there are no welds in the spaces 1340 between adjacent bearing elements 1324. Alternatively, the bearing elements 1324 may be formed as one-piece with the respective cover plates 1323, 1325. Each cover plate 1323, 1325 has two sets of bearing elements 1324. The sets of bearing elements 1324 for the upper cover plate 1323 are arranged in a linear, spaced configuration that is generally aligned with the bearing elements 1314 extending along the upper edges of the gusset plates 1321 in the joint connection structure 1311. The sets of bearing elements 1324 for the lower cover plate 1325 are arranged in a linear, spaced configuration that is generally aligned with the bearing elements 1314 extending along the lower edges of the gusset plates 1321 in the joint connection structure.

As illustrated in FIGS. 150-154, the spaced configuration of the bearing elements 1324 in each set of bearing elements leaves spaces 1340 between adjacent bearing elements on the beam assembly 1317. The bearing elements 1324 are suitably substantially identical to the cuboidal bearing elements 1314 or the trapezoidal prismatic bearing elements 1314' described above, except as noted. As illustrated in FIG. 144A, prismatic bearing elements 1324' on the full length beam assembly 1317 are positioned and arranged so the spaces 1340 between adjacent bearing elements 1324' are wider at the bottom and narrower at the top.

Referring to FIGS. 151 and 153, the full length beam assembly 1317 also includes a pair of vertical shear plates 1350. Another mounting plate 1320F is mounted on each of the shear plates 1350 and an additional set of bearing elements 1324 is secured to each of the mounting plates to mount the bearing elements on the respective shear plate. For example, the bearing elements 1324 are suitably welded to the respective mounting plate 1320F in the manner described above and the mounting plates are suitably welded to the respective shear plate 1350. The shear plates 1350 are connected to the web 1336 of the beam 1319 on opposite sides of the beam so that the bearing elements 1324 secured thereto project laterally from the web. As illustrated, the shear plates 1350 are each connected to the beam 1319 by a connecting member 1354. As illustrated in FIGS. 151 and 153, the connecting member 1354 is suitably a piece of angle iron, although other structures could be used instead.

The vertical shear plates 1350 are suitably attached to the web 1336 of the beam 1319 in a manner that allows selective movement of the shear plates along the longitudinal axis of the beam 1319. As illustrated, in FIGS. 151-153, the web 1336 of the beam 1319 has at least one slot 1356 extending along a length of the beam and each of the vertical shear plates 1350 is fastened to the beam 1319 using a fastener 1358 (e.g., a bolt) in the slot such that the vertical shear plate is selectively moveable relative to the beam along the slot. A single fastener 1358 can extend through the slot opening 1356 to connect the shear plates 1350 on opposite sides of the web of the full length beam, as illustrated in FIG. 155. In the illustrated embodiment, there are three slots 1356 in the web 1336 of the beam 1319 and three fasteners 1358 (e.g., three bolts) are used to secure the shear plates 1350 to the beam. When all of the fasteners 1358 are loosened, the shear plates 1350 can be moved longitudinally along the beam 1319 by sliding the fasteners in the slots 1356. Once the shear plates 1350 are in the desired position such that bearing elements 1324 attached to shear plates 1350 can engage and become interlocked with bearing elements 1314 secured to gusset plate 1321, the fasteners 1358 can be tightened to hold them in place.

The column assembly 1313 suitably includes at least one keeper 1360 (FIG. 140) attached to the column assembly to help hold the shear plates 1350 in the desired position until the bolts 1358 are tightened. In the illustrated embodiment, there are two substantially identical keepers 1360, one on each side of the column assembly 1313. Each keeper 1360 is suitably mounted on an exterior surface of one of the gusset plates 1321. As illustrated in FIG. 140, the keepers 1360 are suitably positioned at an end of the set of bearing elements 1314 that extend along the vertical edge of the gusset plate 1321. Each keeper 1360 is suitably moveable between a first position (illustrated in phantom on the right side of FIG. 143) permitting the vertical shear plate 1350 in the joint connection structure 1311 to be moved toward and away from the gusset plates 1321 and a second position (FIG. 140 and left side of FIG. 143) locking the vertical

shear plate in position with respect to one of the gusset plates. For example, each keeper 1360 is suitably a strip of metal mounted on an outer surface of the gusset plate by a bracket 1362 (FIG. 145), such as a piece of angle iron, by a fastener 1364 (e.g., a bolt) that allows the keeper to be pivoted on the fastener manually between the first and second positions, for example with the use of a tool, such as a hammer.

To form the joint connection structure 1311, the vertical shear plates 1350 are moved toward the ends of the slot 1356 that are more remote from the end of the beam assembly 1317 so the shear plates and the bearing elements 1324 thereon are out of the way during the initial stages of engaging the full length beam assembly with the gusset plates 1321 of the column assembly 1313. The end of the beam assembly 1317 is aligned with the column assembly 1313 so that the bearing elements 1324 on the upper and lower flanges 1332, 1334 of the beam assembly are lined up with the gaps 1330 between the bearing elements 1314 that extend along the upper and lower edges of the gusset plates 1321 on the column assembly and vice-versa. The aligned beam assembly 1317 is lowered until the upper cover plate 1323 contacts the upper edges of the gusset plates 1321, as illustrated in FIG. 143. As the beam assembly 1317 is lowered into this position, the bearing elements 1314 on the upper and lower edges of the gusset plate 1321 interleave with the corresponding bearing elements 1324 on the beam assembly, and vice-versa. As a result, the bearing elements 1314 and 1324 come fully engaged and interlocked. If the trapezoidal prismatic bearing elements 1314', 1324' are used, there is greater tolerance for slight misalignment when the bearing elements start to interleave with one another and the tapered surfaces of the bearing elements help bring the beam assembly 1317 into better alignment with the column assembly 1313 as the beam assembly is lowered into connection with the column assembly.

The keepers 1360 are moved out of the way (e.g., to the first position illustrated in phantom in the right side of FIG. 143) and the shear plates 1350 are moved toward the side edges of the gusset plates 1321, which causes the bearing elements 1324 on the shear plates 1350 to interleave with the bearing elements 1314 along the side edge of the gusset plates 1321. Once the bearing elements 1324 on the shear plates 1350 are fully engaged with the bearing elements 1314 on the side of the gusset plate 1321, the keepers 1360 are moved to the second position in which they limit movement of the shear plates 1350 away from the sides of the gusset plates 1321 to secure the shear plates 1350 in this position. For example, the strips of metal forming the keepers 1360 in the illustrated embodiment are suitably rotated until they extend down from the bracket 1362 along the surfaces of the shear plates 1350 facing away from the gusset plates 1321, thereby securing bearing contact with the shear plates to block possible movement of the shear plates away from the gusset plates, as illustrated in FIG. 140. This provides workers a quick way to hold the shear plates 1350 in position without using any bolts. When the keepers 1360 are in this vertical locking position the shear plate 1350 is attached to the respective gusset plate 1321 by the respective keeper in bearing to connect the beam assembly to the column assembly. In some cases, it may be desirable and suitable to rely (at least temporarily) on the keepers 1360 to hold the shear plates 1350 in position while workers walk on the beam 1319 and perform other tasks. Later the fasteners 1358 can be tightened in the slots 1356 to secure on a permanent basis the full engagement of bearing elements

1324 (attached to shear plates 1350) and the bearing elements 1314 (attached to the gusset plate 1321) in their interlocked position.

When the full length beam assembly 1317 and column assembly 1313 are connected to one another in this manner to form the beam-to-column joint connection structure 1313, the full length beam assembly 1317 is fixedly attached to the gusset plates 1321 of the column assembly 1313 to form an all bearing moment connection that relies exclusively on bearing contact between connecting bearing elements 1314, 1324. At least some of the bearing elements 1314 or 1324 on at least one of the column assembly 1313 and the full length beam assembly 1317 are spaced from each other by a gap (i.e., spaces 1330 or 1340) receiving a bearing element from the other of the column assembly and beam assembly. The bearing elements 1314 of the column assembly and the bearing elements of the beam assembly 1324 are positioned with respect to each other to prevent movement of the beam assembly relative to the column assembly by engagement of the exterior bearing engagement surfaces 1316 of the bearing elements of the column assembly with the exterior engagement bearing surfaces 1326 of the bearing elements of the beam assembly in at least one of a direction along the longitudinal axis of the beam 1319 and a vertically upward direction. In the illustrated embodiment, the exterior bearing surfaces 1316 of the bearing elements 1314 of the column assembly 1313 are in interlocking engagement with the exterior bearing surfaces 1326 of the bearing elements 1324 of the beam assembly 1317 to resist movement of the beam assembly relative to the column assembly in both the direction along the longitudinal axis of the beam 1319 and the vertically upward direction. Moreover, the exterior bearing engagement surfaces 1316, 1326 of the bearing elements 1314, 1324 directly oppose each other about engagement planes that extend transverse to the longitudinal axis of the full length beam 1319. Further, the bearing elements 1314 on the gusset plates 1321 of the column assembly 1313 are free of welded connection to the bearing elements 1324 of the full length beam assembly 1317 and free of bolted connection to the bearing elements of the beam assembly.

FIGS. 158-160 illustrate a beam-to-column moment-resisting joint connection structure of a fifteenth embodiment, which is generally indicated at 1411. The joint connection structure 1411 is identical to the joint connection structure 1311 described above except that at least some of the interlocking bearing elements 1414, 1424 are bolted together to resist possible greater uplift movement associated with applied joint rotation. In particular for each gusset plate, the two innermost (i.e., closest to the column) adjacent bearing elements 1414, 1424 along the top edge of the gusset plate are bolted together (FIG. 159). Similarly, the two outermost bearing elements 1414, 1424 in the linear configuration of bearing elements extending along the top edge 55 of the gusset plates 1421 are bolted together (FIG. 160). The innermost and outermost bearing elements 1414, which in this particular embodiment happen to be two of the bearing elements on the gusset plate 1421, have a bore 1455 extending therethrough in the longitudinal direction of the beam 1419. The respective adjacent bearing elements 1424, which in this case happen to be two of the bearing elements extending from the upper cover plate 1423, have blind bores 1457 that are aligned with the bores 1455 of the bearing elements 1414 in the joint connection structure 1411. The blind bores 1457 are tapped for receiving the threaded end of bolts 1459 extending through the bores 1455 of the adjacent bearing elements 1414 on the gusset plate 1421.

FIGS. 161-174 illustrate a beam-to-column moment-resisting joint connection structure of a sixteenth embodiment, which is generally indicated at 1611. The joint connection structure 1611 is identical to the joint connection structure 1311 described above except as noted. One difference is that the bearing elements 1624 on the upper and lower cover plates 1623, 1625 are secured directly to the cover plate without any mounting plates. For example, these bearing elements are suitably welded directly to the respective cover plate 1623, 1625. Similarly, the bearing elements 1614 extending along the upper and lower edges of the gusset plates 1621 are also secured directly to the gusset plates without any mounting plates. Another difference is that there are no bearing elements extending along the side of the gusset plate 1621 and there is no shear plate or any of the associated features, such as the slots in the web, the connecting member for connecting the shear plate to the web, and the bearing elements on the shear plate. The initial assembly of this joint connection structure 1611 is substantially identical to the assembly of the joint connection structure 1311 described above. However, the assembly is complete once the upper cover plate 1623 contacts the upper edges of the gusset plates 1621. There is no need to perform any additional steps, such as moving a shear plate or other structure to bring additional vertically spaced bearing elements into engagement with one another. This joint connection structure 1611 prevents horizontal movement of the column assembly 1613 and full length beam assembly 1617 in the same manner as the joint connection structure 1311 above. However, this joint connection structure does not prevent movement of the beam assembly 1617 upward relative to the column assembly 1613. The joint connection structure 1611 is suitable for achieving cost reductions in circumstances where gravity can be relied upon to prevent upward movement of the beam assembly 1617 relative to the column assembly 1613 or in applications in which other features of the building will be positioned to prevent upward movement of the beam assembly relative to the column assembly.

It will be understood that the specific connections described in each of the embodiments are interchangeable.

When introducing elements of the present invention or the preferred embodiment(s) thereof, the articles "a", "an", "the" and "said" are intended to mean that there are one or more of the elements. The terms "comprising", "including" and "having" are intended to be inclusive and mean that there may be additional elements other than the listed elements.

In view of the above, it will be seen that the several objects of the invention are achieved and other advantageous results attained.

As various changes could be made in the above constructions, products, and methods without departing from the scope of the invention, it is intended that all matter contained in the above description and shown in the accompanying drawings shall be interpreted as illustrative and not in a limiting sense.

Moment resisting column-to-beam joint connection structures, column assemblies and beam assemblies that are constructed according to the principles of the present invention provide numerous unique features, benefits and advantages. Some embodiments of the present invention may provide an advantage of the fastest steel frame erection time possible with an associated significant reduction in overall field construction cost, while achieving reliable performance and maximum beam-to-column joint structure ductility. Ref-

erence is made to the figures illustrating one of the embodiments to which the advantages and benefits apply.

What is claimed is:

1. A joint connection structure of a building framework comprising:

a column assembly including a column having a longitudinal axis, a pair of gusset plates connected to the column on opposite sides of the column and extending laterally outward from the column and bearing elements operatively connected to the gusset plate and projecting from the gusset plate, the bearing elements of the column assembly each having an exterior bearing engagement surface; and

a beam assembly including a beam having a longitudinal axis, upper and lower flanges, an end portion received between the gusset plates and at least one bearing element operatively connected to the beam and projecting from the beam, the bearing element of the beam assembly having an exterior bearing engagement surface;

the bearing elements of the column assembly and the bearing element of the beam assembly being positioned with respect to each other for engagement of the exterior bearing engagement surface of the bearing elements of the column assembly with the exterior engagement bearing surface of the bearing element of the beam assembly to prevent movement of the beam assembly relative to the column assembly in a direction along the longitudinal axis of the beam, wherein the exterior bearing engagement surface of one of said bearing elements of the column assembly opposes the exterior bearing engagement surface of the bearing element of the beam assembly along the longitudinal axis of the beam and prevents relative movement between the beam assembly and column assembly in a direction along the longitudinal axis of the beam through bearing engagement of the exterior bearing engagement surface of said one of the bearing elements of the column assembly with the exterior bearing engagement surface of the bearing element of the beam assembly.

2. The joint connection structure of claim 1 wherein each of the column assembly and the beam assembly comprises plural bearing elements, each bearing element having an exterior bearing engagement surface, the exterior bearing engagement surfaces of the bearing elements of the column assembly being in interlocking engagement with the exterior bearing engagement surfaces of the bearing elements of the beam assembly to resist movement of the beam assembly relative to the column assembly along the longitudinal axis of the beam.

3. The joint connection structure of claim 2 wherein the exterior bearing engagement surfaces of the bearing elements directly oppose each other about engagement planes extending transverse to the longitudinal axis of the beam and parallel to the longitudinal axis of the column.

4. The joint connection structure of claim 2 wherein the bearing elements of the gusset plates of the column assembly are free of welded connection to the bearing elements of the beam assembly and free of bolted connection to the bearing elements of the beam assembly.

5. The joint connection structure of claim 2 further comprising a mounting plate attached to one of the gusset plates and the beam assembly, a first plurality of the bearing elements being disposed on the mounting plate.

6. The joint connection structure of claim 5 wherein the mounting plate comprises a first mounting plate attached to

39

one of the gusset plates, the structure further comprising a second mounting plate attached to one of the gusset plates, a second plurality of the bearing elements being disposed on the second mounting plate.

7. The joint connection structure of claim 6 further comprising a third mounting plate attached to the beam assembly, a third plurality of bearing elements being attached to the third mounting plate, and a fourth mounting plate attached to the beam assembly, a fourth plurality of bearing elements being disposed on the fourth mounting plate.

8. The joint connection structure of claim 7 further comprising a cover plate attached to one of the upper and lower flanges of the beam, at least one of the third and fourth mounting plates being mounted on the cover plate.

9. The joint connection structure of claim 7 further comprising a shear plate, and wherein the beam includes a web extending between the upper and lower flanges, the shear plate being attached to the web for movement of the shear plate along the longitudinal axis of the beam.

10. The joint connection structure of claim 9 wherein the third mounting plate is attached to the shear plate and arranged so that the exterior bearing engagement surfaces of the bearing elements on the third mounting plate are in engagement with the exterior bearing engagement surfaces of the bearing elements on the second mounting plate attached to one of the gusset plates to resist relative vertical movement between the beam assembly and the column assembly.

11. The joint connection structure of claim 10 further comprising a keeper attached to the column assembly for movement between a first position permitting the shear plate to be moved toward and away from the gusset plates and a second position locking the vertical shear plate in position with respect to one of the gusset plates.

12. The joint connection structure of claim 5 wherein the bearing elements are welded to the mounting plate.

13. The joint connection structure of claim 5 wherein the bearing elements and mounting plates are formed as one piece of material.

14. The joint connection structure of claim 2 further comprising a connecting member attached to the beam, at least one of the bearing elements being mounted on the connecting member.

15. The joint connection structure of claim 14 wherein the connecting member comprises one of a cover plate and an angle iron.

16. The joint connection structure of claim 2 wherein the bearing elements have a cuboidal shape.

17. The joint connection structure of claim 2 wherein the bearing elements are trapezoidal prism shape.

18. The joint connection structure of claim 2 wherein there are plural bearing elements on each of the column assembly and the beam assembly, at least some of the bearing elements on one of the column assembly and the beam assembly are spaced from each other by a gap receiving one of the bearing elements from the other of the column assembly and beam assembly.

19. The joint connection structure of claim 2 wherein the bearing elements operatively attached to the beam assembly are welded to the beam assembly, and the bearing elements operatively attached to the column assembly are welded to the column assembly.

20. The joint connection structure of claim 19 wherein the bearing elements welded to the beam assembly are each welded along only two parallel sides of the bearing element,

40

and the bearing elements welded to the column assembly are each welded along only two parallel sides of the bearing element.

21. The joint connection structure of claim 2 wherein at least some of the bearing elements are bolted together.

22. The joint connection structure of claim 1 further comprising a vertical shear plate operatively attached to the beam of the beam assembly and attached to one of the gusset plates of the column assembly in bearing to connect the beam assembly to the column assembly.

23. The joint connection structure of claim 22 wherein the beam includes a web between the upper and lower flanges, the vertical shear plate being attached to the web for selective movement along the longitudinal axis of the beam.

24. The joint connection structure of claim 23 wherein the web of the beam has at least one slot extending along a length of the beam, the vertical shear plate being bolted in the at least one slot such that the vertical shear plate is selectively moveable relative to the beam along the at least one slot.

25. The joint connection structure of claim 24 further comprising a keeper attached to the column assembly for movement between a first position permitting the vertical shear plate to be moved toward and away from the gusset plates and a second position locking the vertical shear plate in position with respect to one of the gusset plates.

26. The joint connection structure of claim 1 wherein the beam is fixedly attached to the gusset plates of the column assembly to form a moment connection with exclusively bearing contact.

27. A prefabricated column assembly constructed for mounting a beam assembly on the column assembly, the column assembly comprising:

a column;
a pair of gusset plates connected to the column on opposite sides of the column and extending laterally outward from the column, and configured for receiving a beam of the beam assembly therebetween to connect the beam assembly to the column; and

a plurality of bearing elements attached to at least one of the gusset plates in spaced apart arrangement for receiving and interlocking with at least one corresponding bearing element on the beam assembly therebetween for moment connecting the beam assembly to the column assembly, each bearing element having an exterior bearing engagement surface for engaging a bearing element on the beam assembly, the exterior bearing engagement surfaces of adjacent bearing elements being disposed in opposed relation to each other.

28. A prefabricated beam assembly constructed for mounting connection to a column assembly, the beam assembly comprising:

a beam having a web and flanges extending from ends of the web;
a connecting member attached to the beam; and
a plurality of bearing elements, at least one of the bearing elements being mounted on the connecting member, the connecting member being operatively attached to the beam, the bearing elements being positioned on the beam to be received between and interlock with a plurality of corresponding bearing elements on the column assembly for moment connecting the beam assembly to the column assembly, the plurality of bearing elements being free of direct engagement with the web of the beam.
